MAKING-READY MACHINES

Georg Kaldschmidt, Dresden-Weisser, Hirsch, Germany, assignor to VEB Druckmaschinenwerk Victoria, VVB Polygraph, Heidenau, Saxony, Germany

Application May 14, 1953, Serial No. 355,019

7 Claims. (Cl. 101—216)

This invention relates to a making-ready machine for printing surfaces, and particularly for printing surfaces used in rotary sheet printing presses for first side letterpress printing.

The letterpress method is at present at a disadvantage compared with flat-bed and intaglio printing processes, because the printing surfaces have to be made ready according to requirements in order to print out a form. This preparatory work takes much time, particularly in a complicated form, owing to the difference in height of the types of the printing plates and the necessary printing on level surfaces.

In competition with the other two processes letterpress printing will last only if the stoppage times of the press due to making ready are considerably shortened. This can be brought about by performing making-ready operations chiefly outside the limits of the press.

Machines built for attaining this object are known, but they serve only for preparing stereotype plates to be taken up by the plate cylinder of newspaper rotaries, and the impression cylinder thereof presses the web against the plate only when a proof has to be taken.

The invention proposes to reduce the stoppage times of a press in the following manner:

At least two readily exchangeable plate cylinders are used for each rotary press, one of which is operating in the press and the other one is prepared for the next form by a making-ready machine. The impression cylinder placed in this machine is an exact copy of the one working in the press, so that the make-ready sheet can be fully prepared on the machine and transferred to the impression cylinder of the press without further trouble.

Owing to this arrangement, the stoppage time of the press, in case of a change of work, is reduced to a minimum that can hardly be lowered.

The machine according to the invention is particularly intended for cooperation with rotary letterpress machines, though it lies also within the range of the invention to make ready printing surfaces used in other printing processes outside the printing press.

The arrangement of the plate cylinder in the making-ready machine according to the invention is an exact reproduction of that of the plate cylinder operating in the press to permit rapid exchange of a cylinder, the stress being the same as in the press. As for the rest, the making-ready machine with its equipment is so constructed that all necessary work can be performed by it.

The application of the invention accelerates making-ready operations to such a degree that the operating efficiency of a rotary press is not reduced by unnecessary stops. This is accomplished by simultaneously providing the making-ready machine with a plurality of plate cylinders delivered to the making-ready station by way of the top of the frame of the machine, which is constructed to form a track, so that, apart from the plate cylinder just made ready, there are always one or more additional cylinders available in the immediate proximity

2

of the making-ready station to insure a quick and uninterrupted sequence of operations.

The making-ready machine is further provided with a mechanical lifting and lowering device to carry the plate cylinder to be prepared from the track to the front of the impression cylinder disposed inside the frame, and back again. The lifting and lowering device may be driven hydraulically or by compressed air or actuated by a rack gearing or any other mechanical driving means.

For inking the plate cylinder serves a simple two-roller inking apparatus which is started and stopped by means of eccentrics. To insure good distribution provision is made for allowing the inking apparatus to move also in stopped condition.

The plate cylinder is driven via the impression cylinder by a motor which reversibly moves the impression and plate cylinders to and fro and drives also the inking apparatus and the lifting device in a manner regulated by clutches.

To facilitate making the plate cylinder ready for printing means for throwing off impression are provided.

In front of the plate cylinder a folding working table supporting plates and tools is arranged. A size ruler consisting of a graduated transverse ruler fitted with laterally adjustable pointers and a graduated longitudinal ruler insures accurate insertion and adjustment of the plates, though a dial indicator may also serve for this purpose. The impression cylinder, too, possesses a turnable working table on which utensils required for making ready may be deposited within reach of the operator. A similar table fitted with lateral displacement means is used for the registration of sheets.

An example of a form of construction is shown in the drawings, wherein—

Figure 1 is a side view of the making-ready machine according to the invention;

Fig. 2, a front view thereof, partly in section; and

Fig. 3 shows diagrammatically the transport of the plate cylinders.

In the frame 1 the impression cylinder 2 is firmly yet rotatably arranged and engages with its toothed rim 3 a corresponding toothed rim 4 of the plate cylinder 5. For properly inserting the plate cylinder 5 in the rim 3 the impression cylinder 2 possesses a marking tooth cooperating with a corresponding gap in the plate cylinder.

The frame 1 accommodates also the inking apparatus 6 which is put on and off by means of the hand lever 7. 8 is the ink fountain tiltable by the lever 9. The clutch for the drive of the ink fountain can be actuated from

50 both sides of the machine by the handle 10 and lever 11. In front of the plate cylinder 5 a folding working table 12 is disposed in the frame 1, and a similar table 13 is associated with the impression cylinder 2 on the other side of the machine. 14 is the laying-on table, turnable in parallel direction, and fitted with lateral gauges. On the base of the frame 1 the driving motor 15 is positioned which drives the pump 16 and through the gearing 17 the toothed rim 3 of the impression cylinder 2. The clutch for the drive of the impression cylinder is actuated by a hand lever 18 and foot lever 19, respectively disposed on the sides of the impression and plate cylinders.

The hand lever 20 serves for changing impression. On the top of frame 1 rails 21 act as track for the plate cylinders 5. The side walls of frame 1 possess recesses 65 22 in which the plate cylinders to be made ready can be lowered to printing position and then lifted again to the level of the rails 21. Lifting and lowering of a plate cylinder 5 is carried out mechanically by means of a hydraulic lifting device consisting of the two lifting cylinders 23 which are laterally arranged in frame 1 and the vertically movable pistons 24 of which embrace with correspondingly shaped bracket plates 25 the lateral bearing pins of

the plate cylinder from below. Pins 26 lock the pistons 24 when in highest position. The lifting cylinders 23 are operated from the pump 16 by way of pipes 27 for the clutching and control of which serve levers 28, 29. The plate cylinders 5 are on both front ends provided with conical barrel-type bearing housings 30 having a broad peripheral groove 31. The internally conical bearings 32 are displaceable in the side walls of frame 1 and shown in outermost position. By means of the threaded spindles 33 the bearings are positioned far enough on the housings 30 to insure good seating of the plate cylinder 5. The spindles 33 are arranged in guide hoods 34 which externally cover the plate cylinder oiltight and are provided with a pawl 45 to prevent loosening of the bearings during operation. With the peripheral groove 31 the plate cylinder runs on the rails 21.

Fig. 2 shows on the left-hand side a bearing pin 30 in its bearing 32 while the bearing pin seen on the other side is outside the bearing. In this position the plate cylinder 5 is lifted, as indicated in the drawing.

A plate cylinder to be made ready is carried to the machine in the manner according to Fig. 3 which shows the mode of operation of the machine. The plate cylinder to be prepared for printing is transported to the machine on a dual carriage comprising a lower carriage 37 with wheels 36 and an upper carriage 39 with wheels 40, which is pushed on rails 38 of the lower carriage 37. The upper carriage 39 is fitted with folding track bridges 41, 42. The used plate cylinder is dismounted from the press, rolled on the upper part 39 of the dual carriage and together with the part 39 driven out of the press and on the lower part 37 and locked in position. After the dual carriage 37, 39 has been brought to the side of the making-ready machine where the impression cylinder is arranged, as indicated in solid lines in Fig. 3, the track bridges 42 are folded and coupled with the rails 21 of the machine. The plate cylinder 5' is then rolled out of position I and into position II where it remains for the present. In the meantime, the finished plate cylinder 5" has been lifted by the hydraulic device 23, 24 from the lower position I to the upper position II, the dual carriage 37, 39 brought to the side of the machine where the plate cylinder is located (shown in dotted position in Fig. 3) and the track bridge 41 coupled with the rail 21. Thereupon the plate cylinder 5" is rolled on the dual carriage 37, 39 into position III, the bridge 41 turned up, and the cylinder moved to the printing press for mounting. After removal of the plate cylinder 5" from the making-ready station or machine a new cylinder 5' can be rolled on the lifting device 23, 24 and placed in position for preparation to make room for an additional cylinder to be handled by the machine.

When the adjustment of a plate cylinder in the making-ready machine is completed the impression cylinder 2 is made ready. The packing of the impression cylinder of the press and that of the impression cylinder of the making-ready machine are of course alike. After the impression cylinder 2 has been prepared so that a proof can be taken the turntable 14 is placed in laying-on position, the impression cylinder 2 brought into operative position indicated by a mark, the cylinder grippers are opened by actuation of the handle 43, the sheet is pushed against the laying-on gauges of the impression cylinder and the cylinder grippers are closed again by the handle 43.

The plate cylinder 5 having been inked, impression is thrown on, and the cylinders 2 and 5 are set in motion by push button control. If the proof turns out to be

satisfactory the packing of the impression cylinder of the making-ready machine is taken off and pasted on the impression cylinder of the press, so that the press need be stopped only for the time required for moving the plate cylinder out and in and putting on the packing of the impression cylinder.

I claim:
